[57] CLAIM

The ornamental design for a telephone circuit connecting device, as shown.

DESCRIPTION

FIG. 1 is a front elevational view of a telephone circuit connecting device showing our new design;

FIG. 2 is a side elevational view thereof as seen from the right-hand portion of FIG. 1;

FIG. 3 is a side elevational view thereof showing the side opposite that seen in FIG. 2;

FIG. 4 is a top plan view thereof;

FIG. 5 is a bottom plan view thereof; and,

FIG. 6 is a rear elevational view thereof.

FIG. 2.

FIG. 1.

FIG. 4.

FIG. 3.

FIG. 6.

FIG. 5.
